ROLLER SCREEN

Robert George Bridges, San Carlos, Calif.

Application August 27, 1948, Serial No. 46,517

4 Claims. (Cl. 160—28)

1

This invention relates to roller screens and has for one of its objects the provision of improved means in a roller screen installation for protecting the screen against the elements when the same is rolled up within its housing but is connected with a window for withdrawal when the window is opened.

Another object of the invention is the provision of improved means in a roller screen installation for mounting the screen in a window opening, and for guiding the screen during its movement to and from a position extending across a window opening.

A still further object of the invention is the provision of improved means in a roller screen installation for connecting and disconnecting the screen to the window.

Heretofore it has been common practice to support the spring wound roller screens within an elongated housing that in turn is secured to the sill of the window frame for a lower vertically slideable window, or to one or both of the jambs or vertical side frame members of horizontally slideable windows, or to the upper head piece of the frame for the upper one of a pair of vertically slideable windows.

While the present invention is adapted for use with sliding windows of any of the above types, it will be shown as applied to only the lower of a pair of vertically slideable windows because this is the usual and most common structure.

A roller screen housing of the above type is formed with a slot in common practice, which slot may open outwardly of the upper side of the housing. The screen extends through this slot to its connection with the window, which connection is usually made with the lower side of the sash.

Heretofore little if any protection has been afforded for the screen in the housing. During wet and windy weather the window is usually closed and at that time rain and dirt have usually entered the housing through the upper slot resulting in damage to the screen, or at least, to its appearance.

With the present invention, simple means is provided on the screen for substantially closing the slot when the window is closed, and for deflecting dirt and draining water away from the slot.

Also heretofore difficulty has been encountered in providing simple and easily operated means for connecting and disconnecting the screen from the window frame. Inasmuch as the screen is outside the window, the connecting and discon-

2

necting of the same with the frame from within the houses has presented a problem.

With the present invention, the manipulation of the window by a person inside the room is all that is required. To secure one disconnected screen to the frame, it is only necessary to fully lower the window, and to disconnect the same and to sharply move the window to a fully open position. A resistance to such movement to fully open position is established at the final inch of movement or fraction thereof when the window is moved to fully open position. In the normal opening of the window there is no effect on the screen, it will remain securely fastened to the window, but a fairly sharp hard final movement, will disconnect the screen from the window.

Other objects and advantages will appear in the description and in the drawings.

In the drawings, Fig. 1 is an elevational view of an opened window with the present invention installed thereon, which view is from the outside of the window. A portion of the roller screen housing is broken away.

Fig. 2 is a horizontal sectional view, partly broken in length, showing the parting strips of this invention in the conventional sides of a window frame where they have replaced the conventional solid strips.

Fig. 3 is a vertical sectional view taken along line 3—3 of Fig. 1.

Fig. 4 is an enlarged fragmentary view of the outer end of the roller screen showing the shield for the slot in the housing, and also showing the means for securing the screen to the frame.

Fig. 5 is a fragmentary elevational view of the upper end of one of the parting strips showing the stop for releasing the screen from the window frame.

Fig. 6 is an enlarged sectional view through the roller housing.

In detail the screen as illustrated herein is adapted to be secured to the sill 1 of a window frame having opposed vertical sides 2, 3 and a lintel or head piece 4. Upper sash 5 and lower sash 6 are adapted to reciprocably slide vertically in the frame in the usual manner.

The side frame members 2, 3 is the conventional window structure, are formed with parallel opposed channels or grooves 7 in which solid parting strips are secured for guiding the upper and lower windows along paths adjacent each other.

In the present invention these parting strips alongside the lower window are removed, and are substituted by elongated generally tubular members 8 that are rectangular in cross-section.

The opposed sides of said members are slotted at 9 longitudinally thereof adjacent one of the adjoining sides of said member, and stops 10 are secured in the upper ends of these members 8, for a purpose to be later described.

The said slots 9 are adapted to receive the vertical marginal portions of a screen 11 when said screen is moved across the window opening. The screen 11 is supported at the lower side of the window opening on a spring wound roller 12 of the usual type which automatically reminds the screen when tension in the screen is relaxed.

The roller 12 is positioned within an elongated housing 13 which may be rigidly attached to the sill 1. End plates 14 of the housing 13 are provided with holes 15 for securing the ends of roller 12 in the usual manner.

Said elongated housing 13 is substantially square in cross-section having a bottom 16, a top 17, side walls 18 adjacent groove 7 and side wall 19 remote from said groove. The juncture between top 17 and side wall 19 is preferably curved and top 17 is provided with a vertically disposed lip 20 for a purpose to be later described. Lip 20 and side wall 19 are spaced apart providing slot 21 through which the screen 11 is adapted to slide when moved across the window opening.

Secured to the free end of screen 11 is an elongated stiffener 22 (Fig. 4) having two opposed legs 23, 24 connected together at their upper ends and between which the screen 11 is secured. Leg 23 on the side of the screen adjacent the sash is substantially flat and leg 24 is curved outwardly and downwardly at its lower end to form a shield 25. This shield 25 is adapted to cover lip 20 on housing 13 when the sash 6 is in its closed position thereby preventing rain, dirt or other foreign matter from entering slot 13.

Legs 23, 24 are provided on their sides adjacent the screen 11 with a plurality of longitudinally extending projections 26, the projections of leg 23 being in staggered relationship with respect to the projections on legs 24, thereby frictionally securing the free end of screen 11 within stiffener strip 22 when the said legs 23, 24 are thrust towards each other with the screen 11 therebetween.

A longitudinal arcuate projection 27 is provided on the upper end of leg 24 and is adapted to engage spring clips 28 which are secured to sash 6. These clips, preferably two in number have a flat portion 29 which may be secured to sash 6 by any suitable means such as screws 30. Each clip 28 curves outwardly and downwardly from flat portion 29 as at 31 and then back upon itself as at 32 and then terminates in a straight portion 33 curving downwardly and outwardly from said portion 29.

To allow each end of the stiffener strip 22 to enter the relatively narrow slot 9, projections 25, 27 are removed adjacent each end of said strip and legs 23, 24 are compressed to form a relatively slender extension 24 (Figs. 2, 5).

As best seen in Fig. 5 a block 10 positioned within the upper end of tubular guide 8 prevents upward motion of screen 11 beyond a predetermined point by extensions 34 of member 22. Block 10 may be secured within guide 8 by any suitable means such as rivets 35 and is preferably formed of wood to minimize noise upon contact of said block with said extensions.

In operation, when one screen 11 is in its contracted position and projection 25 of strip 22 is in contact with housing 13 and covering slot 21, downward motion of the sash 6 causes clip 28 to

engage with member 22 and securely but releasably connects screen 11 to sash 6 through the spring action of clip 28 on projection 27. When the window is raised in the usual manner upward motion of the sash is prevented when extension 34 contacts block 10 in which position the window is substantially fully open and screen 11 covers the window opening.

If it is desired to disconnect the screen 11 from the sash 6 it is only necessary to move the window sharply to the fully open position and block 10, resisting the upward motion of strip 22, will cause the said strip to be released from clip 28 allowing the spring roller 12 to return the screen to its contracted position with shield 25 covering slot 13. It should be noted in this connection that lip 20 on housing 13 besides serving to exclude rain and dirt from slot 21 also serves as a guide upon which screen 11 may slide thus further preventing the entrance of foreign material through slot 21 of top 17 under the impact of the contracting screen.

Drain holes 36 may be provided in housing 13 at the lower edge of side 19 to provide drainage for any water which may enter the housing through slot 21 in the event that screen 11 is across the window opening during a rain.

Sealing means (not shown), such as rubber strips may be provided between sashes 5, 6 to exclude insects and the like from entering between said sashes. Such structure is old and is not a part of this invention.

Thus it can be seen that the present invention is readily installed and requires no modification of the conventional window other than one simple removal of the parting strip as herein before described. Tubular guide 8 may be connected to vertical window frames 2, 3 by means of screws 37 (Fig. 2) and bottom 16 of housing 13 may be secured to the sill 1 by means of screws 38, access being provided to said screws through drain holes 36.

I claim:

1. In a window frame defining a window opening and a pair of sashes reciprocable in the same direction within said frame longitudinally of two opposed sides of said frame, opposingly opening channels formed in said opposed sides between the paths of travel of said sashes, parting strips in said channels for guiding the said sashes past each other, said parting strips comprising generally rectangular tubular members, the opposed sides of said members each being formed with a longitudinally extending slot, a roller screen secured at one end to one of said sashes and a spring roller secured to one end of said frame supporting the remainder of said screen for rolling and unrolling the screen upon reciprocal movement of the sash to which said one end is secured, opposite marginal portions of said screen being slidably within the said slots in said members upon said movement, and a stiffener secured to one edge of said screen extending into said slots.

2. In a screen installation for the opening in a window frame in which a sash is reciprocably slidable to and from one side of said frame and which installation includes a spring roller and screen windable thereon said roller being secured to said one side and said screen extending across the window opening and the remote end of said screen connected with the said sash, means for automatically connecting and disconnecting said screen to said sash comprising a stiffener strip secured to said remote end of said screen, a

spring clip secured to said sash at its end adjacent said screen, said spring clip having a portion directed toward said screen, yieldably movable towards and from said sash and to a position frictionally gripping said strip between said portion and said sash, an inclined cam surface at the end of said portion facing said strip and engageable with the latter for automatically causing said movement of said portion, and stops secured to said frame in the path of said strip for limiting the movement of the latter together with said sash away from said housing and for automatically pulling said strip from said clip when said sash and strip are forced beyond said stops.

3. In a screen installation including a spring roller and screen windable thereon, said roller rotatably supported within an elongated housing extending longitudinally thereof, a slot extending longitudinally of said housing formed in one side thereof through which one end of said screen may be withdrawn, said housing being secured to the sill of a window opening, a bottom wall on said housing opposite said slot for supporting said housing on such sill, and drain openings formed in one of the walls of said housing along one of the edges of said bottom, openings formed in said bottom wall adjacent said drain openings for reception of fastening elements to secure said housing to said sill, said drain openings providing access to said elements.

4. In a screen installation for the opening in a window frame in which a sash is reciprocably slidable to and from one side of said frame which

installation includes an elongated housing enclosing a spring roller and screen windable thereon and which housing has a slot formed in one side through which one end of said screen projects, said housing being adapted to be secured to said one side of said frame, means for securing the projecting end of said screen to said sash comprising a strip secured to said end and extending longitudinally thereof and a spring clip adapted to be secured to said sash, said strip being formed with a projection projecting outwardly of said strip and directed over said one side of said housing and said clip being formed with a projection directed toward said sash for yieldably engaging said first mentioned projection when said sash is against said one side.
